UNITED STATES PATENT OFFICE.

LEO BLUHM, OF NEW YORK, N. Y.

DESIGN FOR A PRINTED FABRIC.

Application filed July 5, 1923. Serial No. 6,681. Term of patent 3½ years.

To all whom it may concern:

Be it known that I, LEO BLUHM, a citizen of the United States, and a resident of the city of New York, borough of Manhattan, in the county and State of New York, have invented a new, original, and ornamental Design for a Printed Fabric, of which the following is a specification, reference being had to the accompanying drawing, forming a part thereof, which represents a printed fabric showing several repeats of my design, wherein the essential features of the design

comprise a broken plaid, the boundary bands of which are made up of alternate shaded lines and within each of the checkers of the square appear two inscribed squares in different shading, the whole being disposed upon a background of contrasting shading.

What I claim and desire to secure by Letters Patent is:

The ornamental design for a printed fabric substantially as shown and described.

LEO BLUHM.
